(57) **CLAIM**

The ornamental design for a handle, as shown and described.

DESCRIPTION

FIG. 1 is a perspective view of a handle according to the present disclosure;

FIG. 2 is a first side view of the handle of FIG. 1, the opposite side being identical thereto;

FIG. 3 is a front view of the handle of FIG. 1, the rear view being identical thereto;

FIG. 4 is a top view of the handle of FIG. 1; and,

FIG. 5 is a bottom view of the handle of FIG. 1.

The broken lines shown represent unclaimed matter and form no part of the claimed design.

1 Claim, 5 Drawing Sheets---
